UNITED STATES PATENT OFFICE.

LOUIS SCHWARTZBERG, OF CHICAGO, ILLINOIS.

CELLULAR PACKING FOR FRAGILE OBJECTS.

Application filed March 5, 1927. Serial No. 172,974.

My present invention relates to improvements in cellular packing for fragile objects, such as eggs and objects made of glass, china and the like. I prefer to mould or otherwise 5 form my packing from paper pulp or analogous material which is a trifle thicker and softer, but less pliable, than the same amount of stock after the same has been rolled in accordance with the usual practice in manufacturing paper. I am aware that paper pulp has already been used in forming packing, and sheets of such material have been provided having recesses, or cavities or cells of the shape of the articles to be received and 10 packed. Such a construction, however, does not afford facilities for properly receiving objects of different shape and objects of even a similar shape but different sizes. My present invention, however, is so formed as to 15 permit of a distention of the cells or recesses or cavities and to require such a distention upon the insertion of the object to be packed, whereby the packed objects are not only separated from each other in separate cells, but are also 20 restrictively and yieldingly held in their respective cells so as to exclude all movement which would otherwise occur on account of an imperfect fit of the object in the recess.

It will also hereafter be seen that by arranging 25 the recesses or cavities or cells in rows and inclining the walls of adjacent cells of the same row and adjacent rows of cells with respect to each other and providing an area or space of disengagement between the walls between 30 adjacent cells of the same row and the walls between adjacent rows of cells I have introduced an additional spring to the walls of each cell which assists the cell in both conforming with and holding the object placed 35 therein.

While the constrictive holding of the object within the cell is in many cases sufficient for securing its safety, it is in some cases desirable to provide the cells with bottoms, and instead 40 of forming the bottoms directly between the lower edges of the cell walls, I revert the cell wall inwardly and upwardly and then form the bottom of any desired configuration between these inwardly and upwardly reverted edges, whereby there is provided a double annulus at the bottom of each cell which adds materially to both the strength and elasticity 45 of the structure as a whole.

I secure the foregoing objects and results by 50 means of the structure illustrated in the accompanying drawing in which,—

Fig. 1 is a plan of a structure comprising two rows of cells formed in accordance with my present invention;

Fig. 2 is a side elevation of the structure 60 shown in Fig. 1, the forward or near walls of the two cells at the right being broken away to more clearly show the form and nature of the corrugations in the inner walls;

Fig. 3 is an end elevation of the structure 65 shown in Figs. 1 and 2 in which the web between adjacent rows of cells is carried above the cells;

Fig. 4 is a view similar to that shown in Fig. 3, except that the web between adjacent rows 70 of cells is not carried above the cells and may be regarded as being suppressed except in so far as being sufficiently present as to secure the function of connecting the adjacent rows together;

Fig. 5 is a fragmental, perspective, corner view of the structure shown in Figs. 1 to 3 especially showing the length or area of disengagement between the walls between adjacent cells in the same row and the walls between 80 adjacent rows of cells;

Fig. 6 is a plan, similar to Fig. 1, in which the cells are shown without corrugations:

Fig. 7 is a side elevation of the structure shown in Fig. 6 the near walls of the two cells 85 to the right being broken away to more clearly illustrate a form of bottom;

Fig. 8 is a section on line 8—8 Fig. 7;

Fig. 9 is a central vertical section through a cell with a modified form of bottom; and 90

Fig. 10 is a central, vertical, section through a cell showing a still further modified form of bottom.

Similar reference characters refer to similar parts throughout the several views. 95

The structure may be either regarded as a sheet or blank of material in which is provided recesses, cavities or cells, or as parallel rows of cells connected by webs extending between their upper adjacent edges. Such 100 sheets or webs are designated by the reference character 15. The walls, or vertical walls, 16, of the individual cells taper inwardly from their upper to their lower edges, which taper is adequate for maintaining objects in adjacent cells properly separated. In the outside walls of the outside cells are provided one or more, preferably two, corrugations, 17. These exterior corrugations run from the tops to the bottoms of the cells and provide considerable additional vertical stability while at the same time permitting the 105 110

walls to spring, flex or distend outwardly or rather transversely or horizontally by the insertion of an object within a cell. In the walls of the cells facing adjacent rows of 5 cells I also provide corrugations, 18, but these interior corrugations preferably start from a point about a third or a quarter of the distance from the tops of the cells and gradually increase in dimensions to the bottom of the cells. This feature is shown clearly in Figs. 2 and 5. The greater the number 10 of corrugations the greater amount of lateral spring which the cells have, and, also, which is of importance, the more widely the distention occurring in a particular case is distributed around the walls of the cell.

The connections or webs, 15, between adjacent cells of the same row are preferably restricted as much as possible to conserve 20 space, so that the wall of one cell upon reaching the top immediately turns downwardly to form the adjacent wall of the adjacent cell. This is shown in Figs. 4 and 5. In order to secure, or rather retain, the spring 25 arising from the taper of these walls they are cut away or otherwise separated from the walls extending between the adjacent rows of cells, as shown at 19 in Figs. 5 and 8.

In order to increase the spring in the walls 30 between adjacent rows of cells the web 15 may be extended above the tops of the cells, as particularly shown at 20 in Figs. 2, 3, 5, 7 and 8. By properly proportioning these divers features which impart spring to the 35 walls of the cells to the weight and strength of the articles to be packed an unusually high degree of safety may be secured.

When, by reason of the weight of the objects to be packed, or for other causes, it is 40 deemed that the spring given to the walls of the cells is not sufficient for safely holding the objects a bottom may be added as shown in Figs. 7 to 10 inclusive. Instead of extending this bottom directly between the lower 45 edges of the cell walls, I prefer to revert the cell walls inwardly and upwardly, as at 21. The bottom is then extended between the reverted edges either directly, as shown at 22 in Figs. 7 and 8; or with a downward dip 50 as at 23 in Fig. 9; or with a downward corrugation and upward boss, as at 24 in Fig.

10; or, in fact, in any desired manner to suit the form and weight of the objects. The reinforcement secured by the reversion of the side walls of the cells, besides reinforcing 55 the structure as a whole, also serves to restrict the spring of the cell walls to their central areas which is peculiarly desirable with certain shapes of objects.

Having described my invention what I 60 claim as new and desire to secure by Letters Patent is,—

1. A cellular packing consisting of an integral structure moulded from fibrous pulp comprising a series of cells tapering inwardly on all sides from their tops to their bottoms, said cells being disposed in parallel rows and having a connecting web extending between their upper adjacent edges, and the walls between adjacent cells in the same 70 row and the walls between adjacent rows of cells being disengaged at their upper ends.

2. A cellular packing comprising a series of cells tapering inwardly on all sides from their tops to their bottoms, said cells being 75 disposed in parallel rows and having a connecting web extending between their upper adjacent edges, and the walls between adjacent cells in the same row and the walls between adjacent rows of cells being disengaged at their upper ends.

3. A cellular packing consisting of an integral structure moulded from fibrous pulp comprising a series of cells tapering inwardly from their tops to their bottoms, said cells 85 being disposed in parallel rows and having a connecting web extending between their upper adjacent edges, the lower portions of the walls of said cells being reverted inwardly and upwardly and a bottom of desired form extended between said reverted edges.

4. A cellular packing consisting of an integral structure moulded from fibrous pulp comprising a series of cells tapering inwardly 95 from their tops to their bottoms, said cells being disposed in parallel rows, and having a connecting web extending between their upper adjacent edges, the web between cells in adjacent rows being extended above the 100 tops of said cells.

LOUIS SCHWARTZBERG.
